(57) **CLAIM**

The ornamental design for a lighting crank stand, as shown and described.

DESCRIPTION

FIG. 1 is a perspective view of a lighting crank stand, showing my new design;

FIG. 2 is a frontal perspective view thereof;

FIG. 3 is a left side perspective view thereof;

FIG. 4 is a rear perspective view thereof;

FIG. 5 is a right side perspective view thereof;

FIG. 6 is a top plan view thereof;

FIG. 7 is a bottom plan view thereof; and,

FIG. 8 is a frontal perspective view thereof, with legs in retracted positions.

The broken line showings of caster wheels in all figures are for illustrative purposes only and form no part of the claimed design.

1 Claim, 8 Drawing Sheets

FIG. 1

FIG. 7
